TOY VEHICLE

Raymond Lohr, Erie, Pa., assignor to Louis Marx & Company, Inc., New York, N. Y., a corporation of New York

Application February 14, 1936, Serial No. 63,880

18 Claims. (Cl. 46—107)

This invention relates to toy vehicles, and more particularly to a novel form of toy which may be most briefly characterized as a bouncing toy vehicle.

5 The primary object of my invention is to generally improve toy vehicles. A more particular object resides in the provision of an unusual form of toy vehicle suitable for use indoors or outdoors and by children of all ages. In accordance with features and objects of the present invention, the toy when used indoors is incapable of scratching the floor or furniture; it may be used on a table and rolled off the table to the floor; it is practically indestructible regardless 10 of abuse; and it may be dropped and bounced like a rubber ball and may be turned over. In accordance with further features and objects of my invention, the toy is equally advantageously usable out of doors: it may be pulled along the ground by a child running at full speed; it continues in proper operation even if it is jolted, bounced, or turned turtle; and it may be used at 15 the beach in soft sand, or on dirt or mud, as well as on city sidewalks.

20 25 A further object of my invention is to provide the toy with a simulated driver which appears in driving position regardless of which side of the toy is turned uppermost. Still another object of my invention resides in the provision of a spring motor driving mechanism for use in a bouncing toy of the character here disclosed, and more particularly in the provision of automatic stop mechanism for stopping the motor against free unwinding when the vehicle is removed from 30 or bounces away from its running surface.

35 To the accomplishment of the foregoing and other objects which will hereinafter appear, my invention consists in the toy vehicle elements and their relation one to the other, as hereininafter are more particularly described in the specification and sought to be defined in the claims. The specification is accompanied by drawings, in which:

Fig. 1 is a perspective view of a toy embodying 40 features of my invention;

Fig. 2 is a side elevation thereof;

Fig. 3 is a rear end elevation thereof;

Fig. 4 is a section through and is explanatory of the construction of the wheels of the vehicle;

50 Fig. 5 illustrates one of the many possibilities of the toy in operation;

Fig. 6 is a partially sectioned side elevation of a modification arranged for self-propulsion;

Fig. 7 is a partially sectioned plan view there- 55 of; and

Fig. 8 is a partially sectioned side elevation of a modified form of the invention embodying a movable duplex simulated driver and also embodying bell ringing mechanism.

Referring to the drawings, and more particularly to Figs. 1, 2, and 3 thereof, the vehicle toy comprises a compact vehicle body B provided with well-rounded and preferably soft and resilient wheels W. The diameter and location of the wheels are such that the top, bottom, and ends of the body B are housed within the peripheries of the wheels, as will be particularly evident on inspection of Fig. 2. Moreover, the ends of the wheel axles are safely housed well inside the side faces of the wheels, as will be evident 15 from inspection of Fig. 3. The wheels are preferably made of soft sponge rubber and simulate enormously oversized balloon or doughnut tires. The body B is preferably made symmetrical with respect to its longitudinal axis, so that there is 20 no appreciable change in appearance of the toy if it is inverted, the axles preferably being located midway between the top and bottom of the toy body, as is clearly brought out in Figs. 2 and 3.

With this construction, it will be evident that 25 the toy possesses a striking and novel appearance; that it is capable of running on either side; that it cannot injure furniture because the soft sponge rubber wheels act as bumpers for the front and rear ends of the toy and for all 30 sides of the toy including the outside faces at the ends of the axles; and that the toy, because of its simplicity and because of the manner in which it is shielded at every point by the soft 35 resilient wheels or tires, is practically unbreakable.

Considering the construction of the toy in greater detail, the body B is preferably pressed out of heavy-gauge sheet metal and in the present case simulates the body of a racing automobile. The body is given a compact cigar-like configuration and therefore possesses considerable inherent structural strength and rigidity.

The construction of the wheels is best brought out in Fig. 4. I prefer to employ a soft highly 45 porous sponge rubber body 12, through the center of which is passed the end portion 14 of an axle 16. The sides of the sponge rubber body 12 are compressed together by inner and outer washers 18 and 20, washer 18 being slipped over axle 16 ahead of the rubber body to a suitable abutment or shoulder 19, and washer 20 then being added and forced toward washer 18 until the end of the axle is exposed, whereupon the end is riveted over the washer, as is indicated 50 55

at 22. While it is not essential to do so, I prefer to use an ordinary spherical sponge rubber ball, indicated by the broken line 24, because the sponge rubber in this form is standardized 5 and obtainable at low cost, and, more importantly, because I find that a wheel of good appearance and operating characteristics may be thus obtained. The opposite faces of the ball are compressed inwardly to a substantial extent, as is 10 readily apparent from comparison of the solid and broken outlines superimposed in Fig. 4. Because of the importance of shielding the axle end 22 well within the protective side of the wheel, I find it preferable to make the washer 15 20 smaller in diameter than the washer 18, for washer 20 is then embedded to a greater depth than washer 18, and the resulting difference in location is retained throughout the life of the toy.

20 The axles 16 are inserted in and located on the body B in any desired manner. In the present case the axles have shoulders or keys 30 swaged outwardly at opposite sides of the body, as is best shown in Figs. 1 and 3. These keys are so spaced 25 as to permit the axle to turn freely in the body, yet to prevent the axle from shifting axially. The body is thereby centered symmetrically between the wheels.

The toy illustrated in Fig. 1 is of the motor-less or pull type. A small bail 40 is struck outwardly at the center of the forward end 42 of the body and is adapted to receive one end of a pull cord 44. It will be understood that the child holds the other end of the cord and pulls the toy 35 along behind him; and one advantage of the present toy is that, unlike ordinary vehicle toys, it may be pulled along at full running speed, for the toy bounces without injury and it may turn turtle for it runs equally well on either 40 side. I have found that the amusement and play value of the toy may be increased by making the pull cord 44 elastic. A length or strand of ordinary rubber is suitable. This not only provides flexibility in operation as the toy encounters 45 bumps and like obstacles, but also may be intentionally employed to cause the toy to run backward and forward while the child remains at one point, and, by getting up sufficient speed, the toy may be made to skid, as when cracking the whip, 50 or may be made to turn somersault at the end of each reciprocation.

The appearance of the toy may, if desired, be improved by the addition of a simulated driver. In the present case the head of the driver is 55 indicated at 46 and forms part of a figure the lower portion 48 of which is purposely weighted. The figure is pivoted on a pin 50 running transversely through the body. The top and bottom walls of the body are cut away to form similar 60 simulated driving cockpits 52. The figure is so dimensioned as to be rotatable within the body about pintle 50. It always assumes an upright position because of the weighted bottom 48. The head 46 therefore appears at the top, regardless 65 of which side of the toy is turned uppermost. Incidentally, the movement or oscillation of the head during operation of the vehicle, is effective to increase the realism of the toy even when the toy is not upset.

70 Referring now to Figs. 6 and 7, I show a toy vehicle generally similar to that previously described, but differing mainly in being provided with spring motor driving mechanism for self-propulsion of the toy. At the outset, a minor 75 variation in construction may be mentioned,

namely, the manner in which the wheels and axles are located with respect to the body. In the present case, spacer tubes 56 are employed, these tubes being slipped over the axle between the wheels and the body and being so dimensioned as to fill up the space therebetween, thus preventing axial movement of the wheels with respect to the body. As before, a free or running fit is provided, the axles being rotatable in the body.

Coming now to the motor, that here illustrated comprises a winding stem 60 journaled in the side walls 62 of the body B and carrying a main spring 64 the outer end of which is connected to the body at 66, and the inner end of which is secured to the winding stem. The drive of the spring is transmitted through appropriate conventional ratchet mechanism 68 (Fig. 6) to a gear 70 forming a part of a step-up gear train leading to the forward axle 71. Specifically, gear 70 meshes with a pinion 72 20 fixedly related to a gear 74 meshing with a pinion 76 fixedly related to a gear 78 meshing with a pinion 80 mounted directly on the aforesaid axle 71. One end of winding stem 60 is bent to form a key 82, and it will be understood that by winding 25 the key and then releasing the vehicle, it is propelled by the motor. The vehicle runs in a forward direction when running on one side, but runs in a rearward direction when turned turtle. This is not a serious objection, and, if anything, increases the amusement obtained when operating the toy. Moreover, the racer type body here used does not greatly differ at its forward and rear ends, and, in fact, the ends may be made alike, that is, the body may, if desired, be made symmetrical with respect to its transverse axis as well as with respect to a longitudinal axis as is now the case.

Furthermore, when the toy is provided with a rotatable figure, such as the figure 46 previously 40 described (and which has been omitted in Figs. 6 and 7, for simplicity), the change in direction of movement of the vehicle is appropriate and corresponds to a change in the direction in which the head of the figure faces when the toy is inverted. In other words, the figure and motor are so related that the toy in either case runs in the direction in which the figure faces.

It has previously been mentioned that the toy may be bounced much like the rubber balls from 50 which it is largely made. Referring to Fig. 5, for example, I show how the toy may be run on a table 84 without worry or fear, because on falling from the edge of the table, the toy is uninjured and simply bounces to running position, as is 55 indicated by the successive positions 86, 88, and 90. The result is highly pleasing to children, most of whom cherish a secret desire to run a toy vehicle over a table edge or precipice. It should be noted that the toy always lands on four wheels 60 after being bounced, this being due to the relatively rounded configuration at the outside of the wheels and the substantial width of the toy relative to its height, thus making it difficult for the toy to come to rest on its side.

When using the motor-driven form of toy shown in Figs. 6 and 7 in the manner described in Fig. 5 or any equivalent manner, difficulty arises because of the tendency of the spring motor to freely unwind when the wheels are free of the 70 running surface. To overcome this difficulty, I provide top and bottom feeler or stop members 92 and 94 (Figs. 6 and 7) so arranged as to determine whether the vehicle is resting on a running surface, and, if so, to release the motor for un- 75

winding. When the toy bounces or is otherwise removed from a running surface, the bottom feeler moves downwardly and the motor is locked against further rotation until the feeler is again moved upwardly by the running surface.

Considering the arrangement in greater detail, feelers 92 and 94 are formed at the opposite ends of a single piece of rod the center portion 96 of which extends transversely through and is journaled in the body B. Shaft 96 carries an arm 98 to which is pivotally connected the rear end of a detent strip 100. This strip is twisted to lie in a vertical plane at its rear portion, but to lie in a horizontal plane at its forward end or detent portion 102. Part 102 is disposed immediately adjacent one of the gears of the gear train, in this case gear 78. The strip is guided by resting on the spindle 104 of pinion 72 and gear 74. A light coiled spring 106 is tensioned between strip 100 and a suitable hook or lug 108 on the body. The spring is disposed at an angle so as to normally tend to move detent 102 into engagement with the teeth of gear 78. However, when the toy rests on a suitable running surface, here indicated by the line 110, the bottom feeler, in this case feeler 92, is moved upwardly, thus oscillating arm 98 in a clockwise direction, as viewed in Fig. 6, and so moving detent 102 away from gear 78, as shown in Figs. 6 and 7. It will be understood that when the toy is inverted, the feeler 94 functions instead of the feeler 92. It will also be understood that the feelers 92 and 94 are made relatively rounded in configuration and are disposed at a long slope or angle in order not to impede the movement of the toy on the running surface. As shown in Fig. 6, the toy runs in a rearward direction, that is, toward the right as viewed in the drawings. When the toy is inverted, it runs in a forward direction, that is, toward the left, and at that time feeler 94 is disposed in a rearward direction such as will not impede movement of the toy, just as feeler 92 is disposed in a direction such as not to impede movement of the toy toward the right as viewed in the drawings.

Another form of my invention is shown in Fig. 8. The body, wheels, and axles may be constructed substantially as previously described. The construction of the simulated driver is modified, however, with a view to making the driver face forward even when the toy is inverted. Considered in simplest form, this may be done by providing two heads, one at the top and the other at the bottom of the toy. Only the upper head is visible, because the lower head is near the running surface and is concealed by the toy structure.

The arrangement may be elaborated, however, with a view to making it possible to project the driver's head out of the toy body. It will be recollect that the pivoted driver in Fig. 1 is disposed within the toy body, and this is done not only to make rotation of the driver possible, but also to maintain the fundamental condition sought in the present toy, in accordance with which all parts of the toy are shielded within the protective rubber wheels. This protects the toy against injury and protects furniture and the like against scratching.

These objectives are retained in the arrangement of Fig. 8 in accordance with which the top and bottom heads 112 and 114 are preferably formed of material of light weight, for example, outwardly convexed sheet celluloid. The combined figure is mounted on one end of an arm 116 pivoted on a transverse support or shaft 118. Arm 116 is extended beyond shaft 118 and carries

a weight 120 which far overbalances heads 112 and 114. The weight 120 may, if desired, be provided with bumpers 122 which limit its movement and insure silent operation. It will be apparent from inspection of Fig. 8, that the upper head, in this case head 112, is moved out of the cockpit by the descent of weight 120, and that at the same time the bottom head 114 is moved to a safe position well within the toy body B. When the toy is turned over, weight 120 immediately changes position and promptly draws head 112 to a protected position within the toy body, while head 114 is moved upwardly to driving position.

It will be understood that the weighted retractible head arrangement may be used, if desired, with only a single head, and also that the double head arrangement may be employed with the heads fixed in stationary position within the cockpits. These features may be used alone as well as in combination as specifically exemplified in Fig. 8.

The arrangement of Fig. 8 also includes bell ringing mechanism which functions as the toy is drawn along by its pull cord or rubber strand 124. This bell ringing mechanism is so arranged as to function equally well, regardless of which side of the toy is uppermost. Specifically, the forward axle 126 carries a gear 128 which meshes with a pinion 130 mounted on a shaft 132. Shaft 132 carries a disc 134 provided with ring-like bell clapper weights 136, said weights being carried on pins 138 projecting sidewardly from disc 134. The ends of pins 138 are preferably headed sufficiently to hold the weights against axial movement, but the weights are freely movable in a radial direction. A bell gong 140 is mounted close to disc 134 by means of a suitable post or support 142. It will be understood that on rotation of disc 134, the bell clapper weights 136 fly outwardly under centrifugal force and thereupon reach and strike bell 140 as they move past the same.

It is believed that the mode of constructing and using, as well as the many advantages of my improved vehicle toy, will be apparent from the foregoing detailed description thereof. The toy is striking and attractive in appearance, and is practically indestructible in construction and use. It may be rolled off a table or precipice without injury, and instead simply bounces and regains running position. It may be run with either side up. It cannot scratch or injure floors, table tops, furniture legs, or the like, because all of the metal parts of the toy are made compact and are housed safely within the peripheries of the wheels. Not only the top and bottom surfaces but the front and rear ends and the side surfaces and even the axle ends, are all protectively carried well within the soft bumper or shielding surfaces provided by the exaggeratedly oversize balloon-like tires. The toy may be pulled along at full running speed without injury, because it simply bounces or turns turtle, in accordance with the condition of the road surface. Because of the large surface area of the soft rubber tires relative to the small size of the toy body, the toy forms an excellent beach toy which may be used by children in soft sand; and, in fact, I have constructed models of this toy which float even when using a metallic body, this being due to the exceedingly light and porous nature of the rubber wheels. The toy may be mis-handled and practically thrown around without injury to itself or its surroundings.

The toy may be provided with a simulated driver or like figure which turns right-side-up

even when the toy is overturned, and the figure may, if desired, be so arranged as to project out of the top of the toy during operation, yet to move back within the toy body when the toy is inverted. The vehicle may be motor-propelled, and if propelled by a spring motor, special mechanism may be included to automatically lock the motor against unwinding when the vehicle is lifted or bounces away from its running surface. This mechanism functions regardless of which side of the toy is uppermost. When the toy is operated as a pull toy, the cord connected thereto is preferably made of rubber, thus improving the operating characteristic of the toy when drawn along at considerable speed on a running surface. Moreover, the elastic strand may be used to pull the toy to and fro at high speed, and to cause the same to skid sharply about or to turn somersault, all without danger of injuring the toy.

It will be apparent that while I have shown and described my invention in several preferred forms, many changes and modifications may be made in the structures disclosed, without departing from the spirit of the invention, defined in the following claims.

I claim:

1. A toy vehicle comprising a compact slender vehicle body resembling a racing automobile, said body being symmetrical with respect to its longitudinal axis, axles projecting sidewardly for a substantial distance near the front and rear ends thereof midway between the top and bottom of the vehicle body, and relatively large-diameter wheels made wholly of soft rubber mounted at the ends of said axles, said wheels resembling enormously oversize inflated balloon or airplane tires and being so dimensioned and located with respect to the body that the top, bottom, and ends of the body are all located within planes connecting the peripheries of the wheels.

2. A toy vehicle comprising a vehicle body, axles projecting from the front and rear ends of the body, and relatively large soft wheels mounted on said axles, all parts of the body and also the ends of the axles being disposed well inside the outer faces of the wheels.

3. A toy vehicle comprising a vehicle body simulating an automobile racer, axles projecting from the front and rear ends of the body, and relatively large soft rubber wheels mounted on said axles, all parts of the body and also the ends of the axles being disposed well inside the outer faces of the wheels.

4. A toy vehicle comprising a relatively compact vehicle body, axles projecting sidewardly near the front and rear ends thereof, and large soft wheels mounted on said axles, the diameter and location of said wheels with respect to the body being such that the ends of the body are housed within the peripheries of the wheels, and the shape and mounting of the wheels and the axles being such that the ends of the axles are housed well inside the outside faces of the wheels.

5. A toy vehicle comprising a relatively compact vehicle body, axles projecting sidewardly near the front and rear ends thereof, and large soft wheels mounted on said axles, the diameter and location of said wheels with respect to the body being such that the top, bottom, and ends of the body are housed within the peripheries of the wheels, and the shape and mounting of the wheels and the axles being such that the ends of the axles are housed well inside the outside faces of the wheels.

6. A toy vehicle comprising a relatively compact elongated vehicle body resembling a racing automobile, axles projecting sidewardly near the front and rear ends thereof midway between the top and bottom thereof, and large soft rubber wheels mounted on said axles, the diameter and location of said wheels with respect to the body being such that the top, bottom, and ends of the body are housed within the peripheries of the wheels, and the shape and mounting of the wheels on the axles being such that the ends of the axles are housed well inside the outside faces of the wheels. 5 10

7. A toy vehicle wheel comprising a circular body of soft sponge rubber having an axle forced diametrically therethrough, and circular metal washers disposed on said axle at the inside and outside faces of the wheel, said washers being spaced apart along the axle a distance less than the axial dimension of the circular body of sponge 20 rubber, said washers holding said body under sufficient compression to give the wheels the desired shape. 15

8. A toy vehicle comprising a soft sponge rubber ball having an axle forced diametrically 25 therethrough, and circular metal washers disposed on said axle at the inside and outside faces of the wheel, said washers being spaced apart a distance substantially less than the diameter of the ball, said washers holding the rubber therebetween under sufficient compression to give the wheels the desired shape and to safely house the end of the axle within the outside face of the wheel. 30

9. A toy vehicle wheel comprising a circular body of soft sponge rubber having an axle forced 35 diametrically therethrough, and circular metal washers disposed on said axle at the inside and outside faces of the wheel, said washers being spaced apart along the axle a distance less than the axial dimension of the circular body of sponge 40 rubber, said washers holding said body under sufficient compression to give the wheels the desired shape and to safely house the end of the axle within the outside face of the wheel, the outside washer being smaller in diameter than the inside 45 washer.

10. A toy vehicle comprising a vehicle body having a driver's compartment at both the top and bottom, wheels on said body larger in diameter than the vertical dimension of the body, 50 whereby said body may run with either side up, and a figure simulating a driver in said body, said figure being so arranged that a simulated driver's head comes to the top when the vehicle is run with either side up. 55

11. A toy racing automobile comprising a body having top and bottom walls, said walls being cut away to form a driving cockpit at both the top and bottom, wheels on said body larger in diameter than the vertical dimension of the body, 60 whereby said body may run with either side up, and a figure simulating a driver in said body, said figure having a head at its upper end and a weight at its lower end and being pivotally mounted in the body, whereby the head comes to the 65 top when the vehicle is run with either side up.

12. A toy vehicle comprising a vehicle body having a driving cockpit at both the top and bottom, wheels on said body larger in diameter than the vertical dimension of the body, whereby said body 70 may run with either side up, and a figure simulating a driver in said body, said figure having a head at its upper end and a head at its lower end.

13. A toy vehicle comprising a vehicle body 75

having a driving cockpit at both the top and bottom, wheels on said body larger in diameter than the vertical dimension of the body, whereby said body may run with either side up, a figure 5 simulating a driver in said body, said figure having a head at its upper end and a head at its lower end and being movably mounted, and means to elevate the figure relative to the body regardless of which side of the vehicle is turned uppermost.

10 14. A toy racing automobile comprising a vehicle body having top and bottom walls, said walls being cut away to form a driving cockpit at both the top and bottom, wheels on said body larger 15 in diameter than the vertical dimension of the body, whereby said body may run with either side up, and a figure simulating a driver in said body, said figure having a head at its upper end and a head at its lower end and being oscillatably 20 mounted on an arm pivoted in said body and so weighted that the upper head is elevated out of the cockpit of the body and the lower head is drawn into the body regardless of which side of the vehicle is turned uppermost.

25 15. A toy vehicle comprising a relatively compact vehicle body, axles projecting sidewardly near the front and rear ends thereof, large wheels mounted on said axles, the diameter and location of said wheels with respect to the body being 30 such that the top may be run with either side up, a spring motor in said body geared to one of said axles in order to propel the vehicle, and stop means projecting at both the upper and lower sides of the vehicle for automatically stopping 35 said motor against free unwinding when the vehicle is removed from its running surface.

40 16. A toy vehicle comprising a relatively compact vehicle body, axles projecting sidewardly near the front and rear ends thereof, large soft rubber wheels mounted on said axles, the diameter

and location of said wheels with respect to the body being such that the top, bottom, and ends of the body are housed within the peripheries of the wheels, and the shape and mounting of the wheels on the axles being such that the ends of the axles are housed well inside the outside faces of the wheels, a spring motor in said body geared to one of said axles in order to propel the vehicle, and stop means projecting at both the upper and lower sides of the vehicle for automatically releasing said motor for operation when the vehicle rests on a running surface, and for stopping said motor against free unwinding when the vehicle is removed from or bounces away from the running surface.

15 17. A toy vehicle comprising a relatively compact vehicle body, axles projecting sidewardly near the front and rear ends thereof, and large soft rubber wheels mounted on said axles, the diameter and location of said wheels with respect to the 20 body being such that the top, bottom, and ends of the body are housed within the peripheries of the wheels, and the shape and mounting of the wheels on the axles being such that the ends of the axles are housed well inside the outside faces 25 of the wheels, a bell inside said vehicle body, and means geared to one of said axles for operating said bell when the vehicle is run along a suitable running surface with either side uppermost.

30 18. A toy vehicle comprising a relatively compact vehicle body, axles projecting sidewardly near the front and rear ends thereof, large soft wheels mounted on said axles, the diameter and location of said wheels with respect to the body being such that the top, bottom, and ends of the 35 body are housed within the peripheries of the wheels, and a cord connected to the middle of one end of the body for pulling the toy along, said cord being an elastic strand of rubber.

RAYMOND LOHR. 40
